Inventor

J. J. Long,

UNITED STATES PATENT OFFICE.

JOHN JONES LONG, OF ITTABENA, MISSISSIPPI.

FIRE-GRADE.

SPECIFICATION forming part of Letters Patent No. 644,615, dated March 6, 1900.

Application filed August 12, 1899. Serial No. 727,038. (No model.)

To all whom it may concern:

Be it known that I, JOHN JONES LONG, a citizen of the United States, residing at Ittabena, in the county of Leflore and State of Mississippi, have invented a new and useful Fire-Grade, of which the following is a specification.

My invention relates to fire-grates, and has for its object to produce a grate in which the parts are separable, so that they may be easily replaced in case they become burned out or need replacing from any cause.

In the accompanying drawings, in which the same reference-numeral indicates a corresponding part in each of the views in which it occurs, Figure 1 is a front view of a grate embodying my invention. Fig. 2 is a vertical sectional view taken on the line $x-x$ of Fig. 3. Fig. 3 is a horizontal sectional view. Fig. 4 is a detail view of one of the side walls, and Fig. 5 is a broken detail view taken horizontally through one side of the grate-front to show the shape of the vertical groove therein.

Referring more particularly to the drawings, 1 indicates the front wall or main frame 25 of the grate, to which the grate or basket 2 may be secured in the usual manner, and also provided with any preferred form of entrance-opening.

The side walls 3 3 of the grate are detachably secured to the rear of the front wall by means of flanged grooves or channels 4 4, one wall of which, 5, overhangs the channel to form a flange and engages with a flange 6 on the edge of the side wall. This causes the 35 side wall to project rearwardly from the front wall at the proper angle and also holds it against movement away from the front wall. The bottom of the channel is provided with a stop 7, which engages with the bottom of 40 the wall 3 and holds it in position relatively to the basket.

As shown in Figs. 3 and 5 of the drawings, it will be seen that vertical ribs or enlargements A are provided at opposite sides of the 45 entrance-opening in the front section 1 and upon the rear or inner side thereof, and it is in these ribs that the grooves 4 are formed and extend to the upper ends of these ribs, so that the said grooves may be opened at 50 their upper ends in order to readily receive the flanges of the side sections, as will be understood. Also the ribs form a strong and

durable connection between the side sections and the front, permitting of the latter being made comparatively thin and light and without impairing the strength and durability thereof.

The rear wall 8 of the grate is detachably secured between the side walls by means of the grooves or channels 9 9. These grooves 60 may be formed by ledges 10 or other projections, or they may be formed within the walls themselves in the usual manner. The wall 8 is inclined forwardly at the top in the usual manner to form the throat, the rear edge of 65 each side wall being inclined to cause the inclination of the rear wall. The rear wall is held in the proper position relatively to the basket by means of the stops 11 at the bottom of the channels 9, only one of the stops 11 and 70 7 being shown in Fig. 2, the ones upon the other side being duplicates. The rear edge of the basket is held in position or fastened to the rear wall of the grate in the usual manner.

In assembling the several sections of the 75 grate structure the opposite side sections are inserted into the grooves in the front section from the respective upper ends thereof and rest upon the stop-shoulders 7. The back 8 80 is then inserted in the grooves at the respective rear edges of the opposite side sections and from the upper ends thereof and are supported upon the stop-shoulders 11 at the lower ends of the grooves. Thus it will be apparent that the back and side sections are supported solely by the front of the fireplace and may be readily assembled and also taken apart without removing any fastening devices, and at the same time the several sections 85 are fixedly connected together, so as to 90 form a rigid structure capable of supporting the basket-grate.

The front and side walls may be of metal, with the flanges and walls of the channels 95 formed integral therewith or separate therefrom, as desired, and the side walls may be protected by fire-brick; but the rear wall is preferably formed from one or more pieces of fire-brick, although it may be of metal protected with the fire-brick, if desired.

By making the parts separable, as above described, the grate can be taken to pieces and packed in very compact form for ship-

ment and can be readily assembled when it is desired to put it in position in the building. In case any of the parts are destroyed or damaged by the heat from the fire within 5 the grate or from any other cause they can be quickly removed and a perfect part put in place.

The present manner of assembling the several sections dispenses with separate fastening devices, so that the sections are not weakened by perforations for the reception of such fastenings, while at the same time the sections are firmly connected and may be readily assembled and taken apart.

15 Having described my invention, what I claim is—

In an open fireplace, a front section, having an entrance-opening, and vertically-disposed ribs or enlargements located at opposite sides 20 of the entrance-opening and upon the rear or inner side of the section, each rib having a vertically-disposed flanged groove formed

therein and opening outward through the upper end thereof, and provided at its lower end with a stop-shoulder, opposite side sections 25 having vertically-disposed lateral flanges at the front edges thereof, detachably fitting in the respective grooves of the front section, and resting upon the stop-shoulders thereof, each side section having a vertical groove located in its inner face and adjacent to its rear edge, said groove being open at its upper end, and provided with a stop-shoulder at its lower end, and a back section, having its opposite 30 end edges detachably fitting in the respective grooves of the opposite side sections, and resting upon the stop-shoulders thereof.

In testimony that I claim the foregoing as my own I have hereto affixed my signature in the presence of two witnesses.

JOHN JONES LONG.
